UNITED STATES PATENT OFFICE.

CHARLES SOMMER, OF SLOAN'S VALLEY, KENTUCKY.

STAVE-DRESSING MACHINE.

SPECIFICATION forming part of Letters Patent No. 349,323, dated September 21, 1886.

Application filed April 11, 1885. Serial No. 161,967. (No model.)

To all whom it may concern:

Be it known that I, CHARLES SOMMER, a citizen of the United States, residing at Sloan's Valley, Pulaski county, State of Kentucky, have invented new and useful Improvements 5 in Stave-Dressing Machines, of which the following is a specification.

My invention relates to improvements in stave-dressing machines in which staves are 10 dressed for the manufacture of water-tight vessels, such as beer-kegs, oil-barrels, &c.

The object of my invention is to dress the staves on both sides at once, in the same time giving them the desired curve corresponding 15 with the diameter of the keg and providing two thicker end portions, allowing depth for the croze, and leaving a thinner middle portion to facilitate bending, (see Figs. 12 and 13;) furthermore, to provide a practical labor and 20 time saving feed mechanism. I attain these objects by the construction illustrated in the drawings, in which—

Figure 1 is a side view of my machine. Fig. 2 is a longitudinal central section through the 25 upper portion of it. Fig. 3 is an end view of the machine, showing that end where the staves leave it and the driving-pulleys are located.

Fig. 4 is a partial top view showing front end 30 with support for staves when fed. Fig. 5 is a top view of a portion of the chain, showing a pair of grippers. Fig. 6 is a front view of the upper cutter. Fig. 7 shows a knife of the lower cutter. Fig. 8 is a side view of two links of the chain. Fig. 9 is a longitudinal 35 section, and Fig. 10 is an under side view, of the same. Fig. 11 is a top view of one of the guide-rollers B. Figs. 12 and 13 are a side view and cross-section, respectively, of a stave after being dressed.

A is a stout frame, of timber or cast-iron, having at each end a pair of pulleys, B, which guide and propel two endless chains, C. One pair of these pulleys derives motion from the motor by means of the belt D, pulley E, and 40 gear-connection F G.

A friction-pulley, R, preferably of wood or paper, bearing against pulley I, and having link and lever connections J J' J'', pivoted at a' a'', enables the operator to stop the feed 45 mechanism at his will. Friction-pulley R sits on shaft D', which works loosely vertically in one of its bearings D'', and allows the pulley R

to drop sufficiently to come out of contact of pulley I when the hand-lever J'' is released. A stop, t, limits the downward drop. The 55 guide-pulleys B are not round, but polygonal, the length of the sides b corresponding with the length of the links of the chain.

To insure positive motion of the chain the links of it have on their under side indentations c, into which teeth b' of the guide-pulleys fit. Between the guide-pulleys the upper portion of the chain moves on a flat smooth track, c'', to prevent sagging.

To the outward-turned flat side of the two 65 chains, and reaching at right angles across from one to the other, are fastened by set-screws k one or more pairs of grippers, K. These grippers are toothed on their inner side at k', and are set apart a little less than the staves are 70 long, in order to allow the teeth of each gripper to take a firm hold of the stave. By means of the set-screws k, holes c''' in the links of the chains, and slots k'' in the flanges k''' of the grippers, they can be adjusted to any length of 75 stave. There may be as many pairs of grippers as the length of the chain permits, allowing enough space between each pair to give the attendant time to feed.

In feeding into the machine the undressed 80 staves, which are all cut to the same length, the attendant places it on the support H before the second gripper has passed fully around the pulley B. The second or following gripper, in passing around and up in its horizontal 85 position, forces the stave partly in its own and partly into the teeth of the forward gripper, grasping it firmly flatwise between them, all of which is most clearly shown in Fig. 2. The forward end of support H rests on springs 90 h, which yield to any irregularities of the staves while they pass over it. This end of the support is guided, and its height relatively to the grippers is regulated, by two pins, h', descending from the under side of it. These pins 95 pass through the springs h, through a hole in bar h'', which is bolted to the frame, and have on their lower end a nut, h''. This nut limits the upward action of the springs h, but gives free movement to the support downwardly. 100 The other narrow end of the support only yields laterally by means of a slot, i, in it, through which the thinner end of a stationary pin, i', passes. The support is held in place on the

lower side by the enlarged portion of the pin i' on top by a countersunk head, i'' . The pin i' passes through a hole in the cross-bar i''' , bolted to the frame, and is held in place and regulated by means of two nuts, i^{IV} . The two ends of the support are so adjusted vertically that the undressed stave is taken about midway by the grippers. The stave, firmly held between the grippers, passes on now with the chains, and is carried forward by them to the action of the cutters, between which it passes flatwise through. The lower cutter, L , is much like one used in any common planer, except that the knives l are curved out corresponding with the outside diameter of the kegs. (See Fig. 7.) This cutter derives its motion from the main shaft below by means of pulley and belt connection $l' M$. The upper cutter, N , revolving at right angles to the stave, derives its motion from a counter-shaft placed as near as possible in a horizontal line with the cutter-shaft. (See Fig. 3.) It has two sets of knives. The outer one, n , which cuts first, cuts about half of the superfluous wood out, while the next set, n' , having its knives set farther out and corresponding with the inner diameter of the keg, reduces the stave to its final thickness. Knives n and n' are slotted, and can be changed according to the thickness of the staves. The stave is thicker at its two ends, as represented in Fig. 12, to allow for the croze. This is done by the upper cutter, which is lifted at the proper time by two pairs of forming-blocks, O , as high as the additional thickness requires, and placed in pairs on the chain at the proper place by means of countersunk set-screws. These forming-blocks O act directly on two rollers, p , journaled to the lower extensions, p' , of a frame, P .

40 This frame, through which the upper cutter-shaft passes, compels said shaft, and the cutter-head with it, to rise every time it is raised by the forming-blocks acting on the rollers p . The cutter-shaft n^2 extends beyond the frame P at its two ends into two boxes, q'' , which move vertically up and down in a slot, q' , of the two standards Q . Springs q are placed on top of these boxes q'' to force them, and with them the cutter-shaft n^2 , cutter N , and frame P , down as soon as the forming-blocks O have passed from underneath the rollers p . The stave, after passing through the cutters, passes on to the other end of the machine, where, when the first gripper turns down on the guide-pulleys, it is released and drops out by its own weight. (See Fig. 2.)

45 The forming-blocks O may be of various length and thickness to suit different purposes. By means of countersunk set-screws they can be put closer together or farther apart to suit any length of stave.

50 By means of set-screws q''' the tensions of springs q may be regulated.

55 The boxes or bearings l'' of lower cutter, L , move in a slot, a , in the frame, and by means of two set-screws, $l''' l^{IV}$, are adjustable. The drop at the upper cutter is regulated by means of

set-screw s . This drop of the upper cutter and the height of the lower cutter determine the thickness of the stave. 70

The cutters are so adjusted that the grippers K , bent correspondingly, pass in the middle between them, leaving above and below sufficient clearance. (See Fig. 3.) The bearings b'' of pulley B are adjustable longitudinally 75 by means of set-screws b''' , to take up any slack in the chain.

This machine leaves the stave of uniform thickness between the two thicker ends, which form I prefer, as it prevents breaking while 80 bending them.

By means of crossed belt and guide-pulleys the machine may be so arranged that everything is combined in one frame. Care has to be taken in every case that the belt of the upper cutter, which rises and falls, is kept constantly tight. A clutch might be used instead of friction-pulleys $R J$; also, the cutters might be reversed in some cases. By leaving the pattern-blocks O off, straight work can be dressed. 90

Where necessary, some parts of the machine, especially the chain on the lower side, may be suitably protected against dust and splinters by tin caps and shields.

I claim as new and of my invention— 95

1. In a stave-dressing machine, the feed mechanism consisting in the combination of two endless chains, C , having solid links recessed at their inner or bearing surface at c , for teeth b' of driving and guide pulleys B to enter, with adjustable grippers K , toothed at k , and arranged in pairs reaching at right angles across from one chain to the other, bent between the chains to the shape of the stave, so as to clear the cutting-knives, and having flanges k'' , with slots k''' , through which set-screws k''' pass to hold them to the chains. 105

2. In a stave-dressing machine, the combination of two cutter-heads, vertically above each other, with the endless chains of the feed mechanism, being so placed in relation to the cutter-heads that the grippers thereon carrying the stave pass midway between the cutting-knives, one of said cutter-heads revolving in a direction at right angles to the other one. 115

3. In a stave-dressing machine, the combination of the feed mechanism, consisting of chains C , grippers K , and guide-pulleys B , with two cutter-heads vertically above each other, and so arranged that one cutter-shaft is below the upper or feeding portion of endless chains C and at right angles thereto, the other being centrally above the level of said chains and parallel with them, one of said cutter-shafts being adjustable in its bearings l'' , sliding in slot a of frame A , the other vertically yielding, sliding with its bearings q'' in slots q' of standards Q . 120

4. In a stave-dressing machine, the combination of the endless feeding-chains C with adjustable forming or pattern blocks O , which raise one of the cutter-heads at the proper time where different thickness of the stave is required, and supports c'' , for the upper or feeding portion of chains C , which carries the 125

grippers K through between the cutting-knives at the time.

5. In combination with the yielding cutter-head N, the frame P, through which the cutter-shaft n" of the former passes at each side of it, said frame encircling the cutter-head, and having downward extensions p', which carry rollers p, and rest, ordinarily, on the feeding-chains, being held down by springs q in slots 10 q' pressing on bearings q" of cutter-shaft n", said bearings, with shaft n" and frame P, being free to slide up in slots q' of standards Q as frame P is lifted up by the forming-blocks O on chains C passing under the rollers p.

15. 6. In a stave-dressing machine, the combination of the feed mechanism, consisting of the endless chains C, rollers B, and grippers K, with an adjustable support for the staves or feeding-table H at the feeding end of the machine, which latter rests on spiral springs h, guided by pins h' and pin i'.

7. In a stave-dressing machine, the general construction and combination, substantially as above set forth, of two endless chains, C, carrying adjustable grippers K, and two cutter-heads, one below and one above the grippers one cutter-head being yielding to the action of pattern-blocks O on feeding-chains C, to produce varied thicknesses, the knives of the cutter-heads being so shaped and adjusted as 25 to produce, in conjunction with all other parts aforementioned, a stave such as illustrated in Figs. 12 and 13.

In testimony of which invention I hereunto set my hand.

CHARLES SOMMER.
